Attorney

from as by engagement with or detachment from an annular groove 22 in stem 20 while screen 18 is held between spring G and disc 17. Stem 20 extends axially through chamber 4 and a bore 23 of constant diameter in the inner portion 3 of head C which is a close sliding fit with stem 20 and into valve chamber 8, where its end carries a disk 24 frictionally held on the rod and fitting freely in cylinder E. Thus, as plunger B is thrust inwardly by application of axial pressure to portion 11, spring G will be compressed and a mixture of liquid soap and air will be ejected from chamber 4 and through screen 18, perforations 17a of disc 17, counterbore 15 and bore 14 of the plunger and thence outwardly for use from outlet 16.

Now, referring to Fig. 6, it will be noted that the dispenser therein shown is arranged to be adapted to a wall type liquid soap dispenser, which includes a body 30 adapted to support a soap container H in inverted position so that the soap may flow by gravity from the container through a passage 31 into chamber 5' of the dispenser, and in lieu of cylinder A said body has a cylindrical bore into which the dispenser may be inserted and from which it may be removed at will. In this form of dispenser the head C' is of slightly different form than head C of Figs. 1, 2 and 3 for obvious reasons, but otherwise the structure and operation are similar.

In operation, as in Fig. 1, the valve F is unseated as described in the inoperative position of the device and the soap chamber 8 is filled with liquid soap and the stem 20 (herein referred to as a soap piston) is held outwardly (to the right) by spring G, thereby holding the disc 24 against its seat and preventing leakage of soap into chamber 4, while the chamber 4 is full of air sucked in through bore 14 when plunger B returned to outward position. When the plunger B is forced inwardly (to the left) the inner end of the plunger engages the disc 17 and forces stem 20 (the soap piston) inwardly and unseats seal 24, compresses spring 10 in soap chamber 8 and forces valve F into closing position over port 7. Thus, no soap can flow backwardly from chamber 8 into passage 5 or 5' but flows around disc 24 into the space behind it and of a volume equal to the difference between volume of chamber 8 and volume of the stem 20 inserted in the chamber 8. When the plunger is released such action creates pressure in chamber 8 and causes the contents of said chamber to flow into chamber 4 through bore 23 around piston rod 20. The clearance around rod 20 is very slight and the soap is forced through bore 23 at a high velocity and is sprayed into chamber 4. Disc 24 acts as a piston since its diameter is but slightly less than that of chamber 8. Hence, as the liquid is forced around disc 24 at a high velocity and impinges on the sharp edges of the parts, thereby causing turbulence, and is broken up into globules, inasmuch as the pressure in chamber 8 is greater than that in chamber 4, or at any point ahead of seal or piston 24. Thus, under influence of the inwardly thrust and released plunger B the soap is mixed with air resident in chamber 4 and is expelled from chamber 4 through screen 18 and perforations 17a of disc 17 into and from bore 14 of the plunger for use.

It is desirable if not actually necessary to expel all of the soap and air from chamber 4 at each operation. For instance, as shown in Fig. 3, it will be observed that screen 18, disc 17 and plunger B, as at the close of an operation, have

been inwardly moved to an extent whereat the spring G has been fully compressed and the screen is in abutment with the inner end of the head C.

5 Upon release of the pressure on the plunger when in its innermost position, the plunger will be restored to its outermost position by spring G and valve F will remain in closed position almost until the plunger has attained its outermost position. Thus, air is drawn into chamber 4 through bore 14 and outlet 16, perforations 17a and screen 18. Some air, of course, may also be drawn into chamber 8, and any lather remaining in bore 14 and counterbore 15 will be drawn into chamber 4.

It will be observed that, instead of forcing air through a liquid soap, I first break up the liquid into globules and then by forcing the liquid from chamber 8 in a tortuous or indirect path into chamber 4 in a then turbulent state, I further expel the mixture of soap and air through the finely meshed screen 18 and apertures 17a of disc 17 into passage 14 in the form of lather for dispensation through spout 16, at each operation of plunger B. It is important for obtaining the best results to arrange screen 18 and perforated disc 17 substantially as shown, because the disposition of the perforations in the disc and the immediacy of the screen and disc as to position tends to increase turbulence by reason of the increasing velocity of the mixture of soap and air through said elements. The area of the perforations 17a is important and their size relative to the area of chamber 4, the mesh of screen 18 and the area of passage 14 may determine (and usually does) the quality and density of the dispensed material. The chamber 15 also is important for receiving the material dispensed from chamber 4 and wherein said latherous material is allowed to expand before its discharge into passage 14.

A decided advantage of my dispensing valve over those heretofore known and used resides in the fact that I am enabled to force the latherous mixture through the screen by movement of the plunger backwardly and forwardly without sole dependence on air pressure, thereby preventing clogging of the screen and a consequent impairment of the dispenser.

50 It may also be noted that the structure is simple and may readily be disassembled for any purpose, by first removing or loosening screw 13a so that plunger B may be withdrawn from cylinder A, then unscrewing cylinder A from head C, compressing spring G so that disc 17 and screen 18 may be removed from rod 20 and detaching head C from pipe 5 and cylinder E from head C. A unit may be as readily assembled by reversing the above mentioned procedure.

60 Summarizing the aforesaid operations, I apply suitable pressure to a mixture of liquid and air, force the mixture through one or more small orifices, expand the mixture for creating turbulence and a more thorough mixture of soap and air, whereby to provide an aerated soap in the form of a lather for use upon each inward stroke of the plunger, while upon each outward (return) stroke of the plunger, all resident lather and soap in passage 14 and spout 16 are drawn back into chamber 4, thereby cleansing screen 18 at each operation and preventing the clogging thereof before the lather and soap can dry.

I claim:

1. A lather dispenser including: a body containing a liquid soap chamber and an air cham-

ber of greater volumetric capacity than the soap chamber, a plunger having an unobstructed outlet conduit therein and slideable in said body, a stem of constant diameter actuated by inward movement of the plunger and slideable in both the soap chamber and air chamber, a valve controlling the flow of liquid soap into the soap chamber and closed by the inward movement of the stem of constant diameter, a wall dividing the soap from the air chamber and provided with a bore of constant diameter for the passage of the stem, a restricted annular passage for the liquid soap between the inner surface of the bore and the surface of the stem, spring means arranged in said air chamber to urge the plunger outwardly of the body; and foraminous means positioned between the plunger and air chamber so that liquid soap discharged from the liquid soap chamber at high velocity through the restricted annular space on inward movement of the plunger is sprayed into said air chamber and mixed with air to form lather and forced through said foraminous means to form finer lather before entering the conduit in said plunger for discharge therefrom.

2. A lather dispenser including: a body containing a liquid soap chamber and an air chamber of greater volumetric capacity than the soap chamber, a plunger having an unobstructed outlet conduit therein and slideable in said body, a stem of constant diameter actuated by inward movement of the plunger and slideable in both the soap chamber and air chamber, a valve controlling the flow of liquid soap into the soap chamber and closed by the inward movement of the stem, a spring secured at one end to the valve and at the other end to said stem and of such a length when relaxed as to hold the valve off its seat but closing said valve on the inward movement of the stem; a wall dividing the soap from the air chamber and provided with a bore of constant diameter for the passage of the stem a restricted annular passage for the liquid soap between the inner surface of the bore and the surface of the stem, spring means arranged in said air chamber to urge the outlet conduit in the plunger outwardly of the body; and foraminous means positioned between the plunger and air chamber so that liquid soap discharged from the liquid soap chamber at high velocity through the restricted annular space on inward movement of the plunger is sprayed into said air chamber and mixed with air to form lather and forced

through said foraminous means to form finer lather before entering the outlet conduit in said plunger for discharge therefrom.

3. A lather dispenser including: a body containing a liquid soap chamber and an air chamber of greater volumetric capacity than the soap chamber, a plunger having an unobstructed outlet conduit therein and slideable in said body, a stem of constant diameter actuated by inward movement of the plunger and slideable in both the soap chamber and air chamber, a valve controlling the flow of liquid soap into the soap chamber and closed by the inward movement of the stem, a wall dividing the soap from the air chamber provided with a bore of constant diameter for the passage of the stem a restricted annular passage for the liquid soap between the inner surface of the bore and the surface of the stem, spring means arranged in said air chamber to urge the plunger outwardly of the body; an apertured member secured at the outer end of the stem and transmitting inward movement of the plunger to the piston rod; a relatively fine mesh screen supported on said apertured member; a chamber formed in the inner end face of said plunger and into which opens the outlet conduit in the plunger to pass lather forced through said screen and apertured member to the outlet conduit in the plunger so that liquid soap discharged from the liquid soap chamber at high velocity through the restricted annular space on inward movement of the plunger is sprayed into said air chamber and mixed with air to form lather and forced through said screen and apertured member to form finer lather before entering said outlet conduit for discharge therefrom.
